UNITED STATES PATENT OFFICE.

THOMAS H. SIMPSON AND PHILIP T. HANDIGES, OF DETROIT, MICHIGAN,
ASSIGNORS TO THE MONARCH BRAKE-BEAM COMPANY, LIMITED, OF
SAME PLACE.

DESIGN FOR A FULCRUM-JAW FOR BRAKE-BEAMS.

SPECIFICATION forming part of Design No. 29,106, dated July 26, 1898.

Application filed June 20, 1898. Serial No. 684,006. Term of patent 7 years.

To all whom it may concern:

Be it known that we, THOMAS H. SIMPSON and PHILIP T. HANDIGES, citizens of the United States, residing at Detroit, county of Wayne, State of Michigan, have invented and produced a new and original Design for Fulcrum-Jaws for Brake-Beams, of which the following is a specification, reference being had to the accompanying drawings, which form a part of this specification.

In the drawings, Figure 1 is a view in perspective showing features of our design. Fig. 2 is also a view in perspective showing features of our design; and Fig. 3 is a view in section taken on the line 3 3, Fig. 1.

As shown in the drawings, the leading or material features of our design consist of fulcrum-arms A A, separated for a portion of their length, as shown in Figs. 1 and 3, the outline of the outer faces of said arms toward their bases being on an outwardly-projecting curve, as indicated at a a, forming brace portions or ribs a'. Said arms converge at their inner ends with an expanded head A', formed with an open T-shaped slot or recess. (In-

dicated at A².) From the head project jaws A³, having through-orifices a², the slot or recess A² opening outward between the jaws A³. The curved portions a of the arms A project outwardly in a direction of said head. 30 The inner surfaces of the arms A toward their base are formed of outwardly-curved outlines. (Indicated at a³, Fig. 3.) Toward their upper ends the arms A are fulcrumed, as indicated at a⁴, Fig. 2. The inner surfaces of 35 the arms A toward their bases are concaved in cross-section.

Having described our invention, what we claim as new, and desire to secure by Letters Patent, is—

The design for a fulcrum-jaw for brake-beams, as herein shown and described.

In testimony whereof we sign this specification in the presence of two witnesses.

THOMAS H. SIMPSON.
PHILIP T. HANDIGES.
